UNITED STATES PATENT OFFICE.

FRANK W. EDWARDS, OF LOGANSPORT, INDIANA, ASSIGNOR TO THE CHICAGO LUBRICATOR COMPANY, OF CHICAGO, ILLINOIS, A CORPORATION OF ILLINOIS.

SIGHT-FEED LUBRICATOR.

SPECIFICATION forming part of Letters Patent No. 792,764, dated June 20, 1905.

Application filed March 4, 1904. Serial No. 196,599.

To all whom it may concern:

Be it known that I, FRANK W. EDWARDS, a citizen of the United States, residing at Logansport, in the county of Cass and State of Indiana, have invented a certain new and useful Improvement in Sight-Feed Lubricators, of which the following is a full, clear, and exact description.

In two certain Letters Patent of the United States granted to me February 26, 1901, No. 668,814, and September 17, 1901, No. 682,981, is included a certain check-valve interposed between the condenser and the feed-pipe of the boiler, whereby siphoning of the lubricator is prevented upon the arising of conditions conducive to such siphoning—as, for example, should the engine be housed or otherwise left with the water-valve and the steam-supply valve open and the throttle - valve closed. In the present invention an improvement on the check-valve is shown and in addition is provided a special means for heating the oil in the lubricator-oil bowl or receptacle, all as I will proceed now more particularly to set forth and finally claim.

In the accompanying drawings, illustrating the invention, in the several figures of which like parts are similarly designated, Figure 1 is a side elevation, partly in section, showing portions of a condensation-displacement sight-feed lubricator containing the improvements. Fig. 2 is a rear elevation, partly in section, of the oil-bowl. Fig. 3 is a top plan view of the oil-bowl of Fig. 2.

The oil-bowl 1 may be of any approved construction, having a mounting - stud 2 and a condenser 3. This condenser is provided with a nipple 4, and to this nipple is secured a tubular casting 5, having a valve-seat 6, access to which is had through the opening 7, normally closed by a screw stopper or plug 8. In the valve-seat is seated a check-valve 9, opening upwardly and interposed directly between the boiler steam-pipe 10 and the condenser, so that should a so-called "vacuum"

be produced at any point below the check-valve said check-valve will seat, and thus prevent the siphoning of the condenser and lubricator.

11 is one of the circulating-pipes connected with the engine-valve oil-pipe, it being understood that there are two such circulating-pipes.

12 is the air-pump feed-circulating pipe, and in this instance this pipe is connected with a nipple 13 on the oil-bowl. A second nipple 14 is applied to the oil-bowl, and it is connected by a pipe 15 with the oil-pipe 16. The two nipples 13 and 14, and consequently the pipes 12 and 15, are connected by a U-shaped pipe 17, erected vertically in the oil-bowl and extending to nearly the bottom of said bowl, so as to impart its heat to the oil in said bowl.

18 is a suitable inlet to the oil-bowl for filling purposes, and it is adapted to be closed by a screw cap or plug.

As herein shown, the heater-pipe 17 is a part of the air-pump feed-circulating pipe; but obviously it might be made a part of the engine-cylinder feed - circulating pipe. Since this pipe is connected with the steam-supply pipe 10 through pipe 12, it is obvious that the oil or lubricant will be heated before it passes out of the bowl to the air-pump feed and into the oil-pipe leading to the air-pump, thus answering the double purpose of heater and steam-circulating pipe.

It is to be noted that the casting 5 embodies in a single integral structure nipples for the condenser connection and also for the steam-pipe and several circulating - pipes' connections, and therefore avoids the necessity of a great number of joints heretofore used.

The invention is not limited to the form of heater-pipe 17 herein shown or its described arrangement so long as said pipe extends sufficiently into the oil-bowl to heat its contents and also serves to connect the circulating-pipes.

As already stated, the check-valve acts automatically to prevent siphoning when, as,

for example, the engine is housed or otherwise left with the water-valve (connected, for instance, with the lubricator, as at 43, Fig. 1) and the steam-supply valve (not shown, but as 5 usual) open and the throttle-valve closed.

What I claim is—

1. In a sight-feed lubricator, an oil-bowl, a condenser mounted thereon and provided with a top nipple, and a tubular casting connected 10 directly to the nipple on the condenser, and provided with integral means for receiving the steam-boiler and circulating-pipes' connections, there being an integral valve-seat interposed directly between the condenser connection and the boiler connection, and a check- 15

valve arranged in said seat, substantially as described.

2. In a sight-feed lubricator, an oil-bowl provided with two external nipples applied to its top, a U-shaped pipe depending from said nipples into the oil-bowl, and means to circulate steam through the nipples and pipe, substantially as described. 20

In testimony whereof I have hereunto set my hand this 2d day of March, A. D. 1904. 25

FRANK W. EDWARDS.
